COMBINATION BENCH AND RECEPTACLE

Walter L. Campbell, St. Petersburg, Fla.

Application August 6, 1952, Serial No. 20,931

Term of patent 14 years

(Cl. D15—11)

To all whom it may concern:

Be it known that I, Walter L. Campbell, a citizen of the United States, residing at St. Petersburg, in the county of Pinellas and State of Florida, have invented a new, original, and ornamental Design for A Combination Bench and Receptacle, of which the following is a specification, reference being had to the accompanying drawing forming part thereof.

In the drawing:

Fig. 1 is a perspective view of a combination bench and receptacle, with the cover separated from the receptacle, showing my new design.

Fig. 2 is a top plan view thereof with the cover removed.

Fig. 3 is a top plan view with the cover in closed condition.

Fig. 4 is a side view with the cover spaced from the receptacle.

Fig. 5 is a sectional view taken through the receptacle and with the cover spaced from receptacle.

I claim:

The ornamental design for a combination bench and receptacle, substantially as shown.

WALTER L. CAMPBELL.
